DEVICE FOR APPLYING VISCOUS LIQUIDS

Roland Kennedy Fraser, Andover, Mass., assignor to Tyer Rubber Company, Andover, Mass., a corporation of Massachusetts

Application April 8, 1943, Serial No. 482,287

5 Claims. (Cl. 91—62.5)

The present invention relates to devices for applying viscous liquids as, for example, cement to rubberized fabric in the manufacture of waterproof garments.

In the manufacture of such garments it is the practice, after the several parts have been cut out from the rubberized fabric to the desired shapes, to apply a strip or band of cement to the edges of the material where they are to be joined, these parts then lying flat upon the table or bench. At the present time the application of cement is made either with a brush or by the finger of the operator from a supply of cement in an open can or other container. These methods are objectionable because of the difficulty in regulating the amount of cement that is applied, there being a tendency to apply too heavy a coating by the brush or finger when it is first used immediately after dipping in the cement pot, and too light a coating just before the brush and finger is again dipped into the cement. Only from long experience can the operators become sufficiently skillful with the brush or finger to maintain a reasonably even coating of cement. Furthermore, there is always the danger of the cement dripping from the brush or finger as it is transferred from the pot to the work, and in addition, a substantial amount of time is lost in the repeated movements of the brush and finger at frequent intervals between the work and the pot.

It is the object of the present invention to produce a device which will supply a uniform strip or band of the viscous liquid, such as cement, directly to the work from the container itself, in such amount as required by the work and determined by the operator, in a single continuous movement or stroke of the device, with no interruptions or loss of time, and without danger of accidental dripping or spattering of the liquid on the work, all with little training or previous experience required on the part of the operator.

To these ends the present invention consists of a container for holding a supply of liquid, such as cement, and having a spout with a discharge opening or slot on its underneath side and a liquid controlling lip immediately above the discharge opening, the parts being so constructed that when the container is drawn over the work with the spout in contact therewith, the liquid or cement will be applied uniformly to the work in an amount varying with the inclination at which the container is held.

In the accompanying drawing in which the invention is illustrated in a device particularly designed and adapted for the application of cement to flat pieces of rubber or rubberized material,

Fig. 1 is a perspective showing the complete device; Fig. 2 is a vertical sectional view on line 2—2 of Fig. 1 showing the device in operative position; and Figs. 3, 4 and 5 are fragmentary vertical sections, on an enlarged scale, showing the control or regulation of the amount of cement being applied according to the inclination of the device as it is drawn over the work by the operator.

10 As shown in Figs. 1 and 2, the device comprises a cement container having a flat bottom 11 and back 13, with sides 15 converging at the front and an inclined front wall 17 extending upwardly and outwardly from the bottom, the sides and bottom forming a contracted portion or spout. Conveniently, the bottom, back and front walls are formed in a single piece of metal with the turned over edges 19 united by solder, brazing, or other convenient manner, to the two side walls 15.

15 The sides 15 are separately formed, each with a rounded downward extension or member 21 at its front end, and with inturned flanges 23 along the front portion of its top edge. Between the front ends of the sides is a liquid controlling lip 25 comprising the top portion 27 forming an extension of the flanges 23 and a wall portion 29 inclined to the top portion, as shown in Figs. 2—5. This wall portion 29, it will be noted, is off-set 20 from the plane of the front wall 17, and to a greater extent at its lower free edge than where it joins the top portion 27, thus inclining such wall portion 29 inwardly with respect to the front wall 17.

25 The front wall 17 terminates short of the free edges of this portion 29 so that a discharge opening or transverse slot is formed across the upper end of the container through which the liquid can flow or be drawn when the device is tipped and drawn along the work, as shown in Fig. 2, 30 the shape of the parts adjacent the slot being such as to direct the flow outwardly along and beneath the wall portion 29.

35 To prevent the spilling of the liquid when the device is being used, a top closure 31 has been 40 provided for the front end of the container, and to facilitate cleaning of this portion of the container the closure is made removable, by having a cross-piece 33 secured to the closure by the screw 35, screwed into the cross-piece and its 45 boss 37, the ends of the cross-piece passing beneath the flanges 23 of the sides 15.

For the convenience of the operator a handle 39 is provided, attached to the back wall of the container by means of screws 41, the handle 50 being of such length that its free end is flush with

the bottom of the container so that when not in use the container is firmly supported upon its flat bottom and end of the handle, with the cement contained in the lower portion below the discharge opening 30.

The operation of the device is as follows. A suitable amount of cement having been poured into the container as it stands upon its flat bottom 11, the operator lifts it by the handle and positioning it over the work tips the front end down into contact therewith and draws the device along the work with a firm, quick stroke. During this movement the device is in the position shown in Fig. 2.

It will be noted that the extensions 21 adjacent the discharge opening support the end of the container slightly above the surface of the work, as shown in Figs. 3, 4 and 5. If a heavy application of cement is desired, the device will be held by the operator with the front wall 17 substantially parallel with the surface of the work, as shown in Figs. 2 and 3. In this position, the lip 25 is held well above the work and as the device is drawn along, a thick band or ribbon 43 of cement is applied of a width corresponding to the width of the discharge opening or slit 30, the extensions 21 also acting to prevent the lateral spreading of the cement as it leaves such opening.

Where a lighter application is desired, the operator tips the device by elevating the handle so that the parts then assume the position shown in Fig. 4, the extensions 21 being so shaped that the lip 25 is brought nearer the surface of the work and a thinner ribbon of cement 45 is applied.

If a still lighter application of the cement is desired, the device is inclined still further towards the vertical so that the lip 25 is brought still closer to the work and a still thinner ribbon of cement 47 is laid thereon. Thus the operator, by varying the inclination at which the device is held while in use, regulates the amount of cement applied. It is only necessary for the operator to maintain the same angle and draw the device at the same speed to insure a uniform, unvarying amount of cement upon the work throughout the entire seam. Furthermore, the device is so simple to use that only a very short time is required for the operator to learn the proper speed for the cement-applying stroke and inclination of the device for any particular kind of work.

All danger is avoided of spattering or dripping of the cement as where the brush or finger method is employed, and not only is a more uniform and satisfactory result secured, but the cement is applied much more expeditiously, as the supply of cement need be replenished only occasionally as compared with the repeated and frequent dippings of the brush or finger into the cement holder.

At the end of the day it is only necessary to rinse or wash out the container with the proper solvent, thus reclaiming whatever cement is left on the walls and bottom of the device, as well as leaving the device clean and ready for another day's use.

While in the accompanying drawing the invention has been shown as embodied in a specific construction designed for a particular use, it is to be understood that it may be embodied in many other different forms and constructions within the meaning and scope of the appended claims. Nor is the invention necessarily lim-

ited to devices for the application of cement, as it may be used for applying many different substances to various kinds of materials and surfaces.

Having thus described the invention, what is claimed is:

1. A device for applying viscous liquids, comprising a container adapted to be moved over the work in contact therewith to apply liquid thereto, and having a front wall extending upwardly and outwardly and provided with a discharge opening adjacent its top end the section of the wall between said top and the opening forming a liquid-controlled lip, and means extending outwardly from the front wall adjacent the discharge opening and the lip to prevent the spreading of the cement laterally as it is discharged from the opening, said means having curved outer edges to engage the work for supporting the front end of the container with the lip spaced at variable distance from the work to vary such spacing in accordance with the inclination at which the device is held by the operator while it is moved over the work, thereby to regulate the rate of discharge of the liquid through said opening and onto the work.

2. A device for applying viscous liquids, comprising a container adapted to be moved over the work in contact therewith to apply liquid thereto and having at its front end a pouring spout provided with a permanently open discharge opening positioned on the under side of the spout and adjacent the front end thereof, a liquid control lip above the opening, and supporting means mounted solely upon the device adjacent the opening and extending outwardly beyond the spout to engage the work, said means being shaped to pivotally support the front end of the container with the lip spaced at a variable distance from the work in accordance with the inclination at which the device is held by the operator while it is being moved over the work, thereby to regulate the rate of discharge of the liquid through said opening and onto the work, the spout being free from extensions at its front end to permit the free tipping of the device about said supporting means.

3. A device for applying viscous liquids, comprising a container adapted to be moved over the work in contact therewith to apply liquid thereto, and having a front wall extending upwardly and outwardly provided with a permanently open discharge opening closed at its ends adjacent the top end of said wall and spaced therefrom by a narrow section of wall forming a liquid controlling lip, and supporting means mounted solely upon the device adjacent the opening and extending outwardly beyond said front wall to engage the work, said means being shaped pivotally to support the front end of the container with the lip spaced at variable distance from the work in accordance with the inclination at which the device is held by the operator while it is moved over the work, thereby to regulate the rate of the discharge of the liquid through said opening and onto the work.

4. A device for applying viscous liquids, comprising a container adapted to be moved over the work in contact therewith to apply liquid thereto, and having a front wall extending upwardly and outwardly provided with a permanently open discharge opening adjacent the top end thereof and spaced therefrom by a section of wall to form a liquid controlling lip, and supporting means extending outwardly from said wall ad-

adjacent the opening to engage the work and shaped pivotally to support the front end of the container, with the lip spaced at variable distance from the work in accordance with the inclination at which the device is held by the operator while it is being moved over the work, thereby to regulate the rate of discharge of the liquid through said opening and onto the work.

5. A device for applying viscous liquids, comprising a container adapted to be moved over the work in contact therewith to apply liquid thereto, and having a substantially flat front wall extending upwardly and outwardly thereof with a discharge opening spaced adjacent the top end thereof, the section of the front wall between said

top end and the opening forming a liquid control lip, the lip being inclined downwardly and inwardly of the wall of the container, and supporting means mounted solely upon the device and extending outwardly beyond the wall to engage the work and shaped pivotally to support the front end of the container with the lip spaced at variable distance from the work in accordance with the inclination at which the device is held by the operator while it is being moved over the work, thereby to regulate the rate of discharge of the liquid through said opening and onto the work.
